UNITED STATES PATENT OFFICE.

WALTER WINFIELD O'HARA, OF TORONTO, CANADA.

COMBINED SPLASH-BACK AND TOWEL-RACK.

SPECIFICATION forming part of Letters Patent No. 439,846, dated November 4, 1890.

Application filed June 5, 1890. Serial No. 354,349. (No model.)

To all whom it may concern:

Be it known that I, WALTER WINFIELD O'HARA, commercial traveler, of the city of Toronto, in the county of York, in the Province of Ontario, Canada, have invented a new and useful Combined Splash-Back and Towel-Rack, of which the following is a specification.

The object of the invention is to design a combined splash-back and towel-rack in which the frame will hold the material used stretched taut and yet may be easily taken apart when it is desired to change the material; and it consists, essentially, of placing the material on two cross-rod which are held apart at each end by the spring extension-arms which form racks for the towel, as hereinafter more particularly explained.

Figure 1 is a perspective view of my combined splash-back and towel-rack. Fig. 2 is a perspective view showing it applied as a picture-frame and stretcher. Fig. 3 is a skeleton view of wire frame.

In the drawings like letters of reference indicate corresponding parts in each figure.

A and B are the top and bottom rods, and C the material forming the splash-back.

D are the spring-wire arms which fit into the holes a and b in the top and bottom rods, respectively. The spring-wire arms D are made so as to form racks d and e for the reception of the towels, while a sponge F, as indicated, or other articles may be suspended from them.

It will be seen that as the arms D are made of spring-wire, the rods A and B are so held apart that the material is held stretched taut

and yet the ends of the arms may be easily removed from the holes a and b, and the rods removed when it is desired to change the material.

On reference to Fig. 2 it will be noticed that I can utilize my frame as a stretcher or picture-frame, the arms being used in this case, as indicated, to support a fancy scarf or other desired ornamentation.

In Fig. 3 I show the cross-rod A and B made of wire and connected by the upright wire rods E and F, which are sharpened at their ends so that a towel or other material may be slipped over their ends to form the splash-back. In this case the ends of the rods A and B are formed into loops f, so as to receive the ends of the spring-wire arms D.

What I claim as my invention is—

1. In combination with the rods A B for supporting the material C, spring-arms D, composed of wire interposed between the rods A B at each end and adapted to hold the material C taut thereon, the said arms D being bent intermediate of their length to form racks d e, whereby the said arms form both supports and rack, substantially as described.

2. The rods A and B, having end loops f, and the vertical connecting-rods E and F, sharpened at their ends, in combination with the wire arms D, forming towel-racks d and e, substantially as and for the purpose specified.

WALTER WINFIELD O'HARA.
